(57) **CLAIM**

The ornamental design for an orthodontic lingual ligature, as shown and described.

DESCRIPTION

FIG. 1 a perspective view thereof;

FIG. 2 is a side view thereof;

FIG. 3 is a top view thereof;

FIG. 4 is a bottom view thereof; and,

FIG. 5 is a front view thereof.

The broken lines shown in the figures represent portions of the orthodontic lingual ligature and form no part of the claimed design.
